UNITED STATES PATENT OFFICE.

WALLACE WILLETT, OF EAST ORANGE, NEW JERSEY.

SPARK-PLUG.

1,247,049.

Specification of Letters Patent. Patented Nov. 20, 1917.

Application filed June 2, 1915. Serial No. 31,648.

To all whom it may concern:

Be it known that I, WALLACE WILLETT, a citizen of the United States, and resident of East Orange, in the county of Essex and State of New Jersey, have invented certain new and useful Improvements in Spark-Plugs, of which the following is a specification.

My invention relates to improvements in spark plugs of the type particularly designed to be mounted on internal combustion engines to produce the firing spark in the combustion chamber.

The sparking points or electrodes of spark plugs now in general use frequently become fouled and sometimes short circuited by the deposit of carbon on the sparking surfaces. It is the present practice when a spark plug becomes fouled either to remove one of the electrodes from the plug without unscrewing the plug from the engine, or to unscrew the entire plug from the engine casing. By the former plan the sparking surface or surfaces on only one side of the circuit are cleaned. By the latter plan the threads in the engine casing are subjected to considerable wear. This wear is cumulative in the engine casing, because the plugs are replaced from time to time as they wear out, and therefore each fresh plug presents a new thread to wear the threads in the engine casing. By either plan it is necessary to replace the entire plug whenever a plug is worn out.

The object of my invention is to provide a simple form of spark plug of readily demountable parts, the outer containing shell or casing of which may be detachably secured in the wall of the combustion chamber with the electrodes and insulating member thereof constituting a removable unit for insert in and removal from the shell. By this construction all of the sparking surfaces may be removed for cleaning without disturbing the shell screwed into the engine casing, and in order to replace a defective plug it is only necessary to substitute one or more of the parts of the demountable unit without disturbing the shell which is screwed into the engine casing.

Various other objects and advantages of the invention will be in part obvious from an inspection of the accompanying drawing and in part will be more fully set forth in

the following particular description of one form of mechanism embodying my invention, and the invention also consists in certain new and novel features of construction and combination of parts hereinafter set forth and claimed.

In the drawings:

Figure 1 is a sectional view taken axially through a preferred embodiment of my invention shown mounted in position in the wall of a combustion chamber;

Fig. 2 is an enlarged end view of the sparking end of the spark plug; and

Figs. 3 and 4 are each compound views showing a side elevation and an end view respectively of the two spark gap forming members.

In the following description and in the claims, parts will be identified by specific names for convenience of expression but they are intended to be as generic in their application to similar parts as the art will permit.

In the drawings there is shown a portion 5 of the wall outlining the combustion chamber of an engine. The wall is provided with a screw threaded opening 6 for the insertion of a spark plug as is usual with devices of this character. A spark plug 7 is inserted in this opening and comprises a shell container 8 having a reduced end 9 screw-threaded into engagement with the opening 6. This shell is provided with a bore 10, the upper end of which is screw threaded as shown at 11, the lower end of which is frusto-conical as shown at 12 with the smaller end adjacent the inner end of the shell, and the intermediate portion of the bore cylindrical as shown at 13. The frusto-conical portion 12 is reduced from the cylindrical portion to form a shoulder 14 providing a seat for a packing ring 15. The lower end of the shell is concaved to form an electrode containing recess 16.

The bore is adapted to contain a removable unit comprising three elements, an insulating core 17 and two co-acting spark gap forming members 18 and 19 carried thereby. The insulating core 17 is preferably formed of porcelain and enlarged intermediate its length to form a cylindrical flange 20 designed to fit within the cylindrical portion 13 of the bore and to overlap the shoulder 14. Opposite sides of the flange are rounded

into the end portions of the core. The lower portion of the core is tapered toward its lower end with substantially the same angle of taper as the frusto-conical portion 12 of the bore.

5 The member 18 is in the form of a conducting rod which extends longitudinally through the core 17, projects beyond opposite ends of the same and has its lower end provided with a plurality of electrodes 21, which, in this embodiment of the invention, are shown to be three spheres projecting laterally from the rod and arranged 120° apart in the form of a circle. The upper end of the conducting rod is screw-threaded as shown at 22 and co-acts with the cap 23 fitting the upper end of the core and with the nut 26 to form the usual binding post.

10 The member 19 is formed of a frusto-conical sleeve 27 designed to be fitted to the tapered portion of the core with a frictionally tight fit. The upper end of the sleeve is formed into an outturned flange 28 designed to fit between the curved face of the flange 20 and the ring 15. The small lower end of the sleeve 27 is provided with a plurality of electrodes 29, in this embodiment of the invention shown to be three in number, projecting downwardly and slightly inwardly from the end of the sleeve and adapted to be disposed between the electrodes 21 to form six spark gaps as shown in Fig. 2, with each electrode disposed between two electrodes of opposite polarity.

15 30 The removable unit is positioned in the shell with the electrodes in the recess 16 and is removably held in place by a bushing 30 engaging the outer threaded end 11 of the bore. This bushing has a rounded end 31 designed to engage the rounded top of the flange 20 to force the unit into engagement with the packing ring 15.

35 Should it be desired to clean the electrodes the bushing is unscrewed and the unit including the electrodes and insulating core is simply lifted out of the shell container 8 leaving the shell container in its screw-threaded engagement with the engine casing. This provides a ready access to both sets of electrodes while mounted in their spark gap forming position, but should it be desired to separate the elements forming the removable unit it is merely necessary to loosen the nut and washer forming the binding post and the conducting rod may be withdrawn from the core. The sleeve may then be pulled off the core and the parts separately cleaned.

40 45 50 When assembled the position of the electrodes relative to each other may be varied from a position exteriorly of the engine casing by rotating the cap 23 which will raise or lower the electrodes 21 relative to the electrodes 29 and there is thus provided a self-cleaning construction.

The bushing which constitutes the locking means for holding the parts in position, the binding post and the unit containing the spark gap forming members are all accessible from the outside of the engine casing 70 and do not require the use of any special tool for mounting the several parts in position.

55 By means of a device of this character it is obvious that there is no necessity for removing the container from the engine casing and in this way the threads are not worn and the spark plug is always securely mounted in place. Either of the electrodes may be removed for cleaning or renewal without disturbing the portion of the plug which is screwed into the engine casing. But even if the entire plug is removed and replaced when it is worn out, the threads in the engine casing will not be materially worn, 85 because this replacement does not take place very frequently.

60 65 While I have shown and described, and have pointed out in the annexed claims, certain novel features of my invention, it will be understood that various omissions, substitutions and changes in the form and details of the device illustrated and in its operation may be made by those skilled in the art without departing from the spirit of the 95 invention.

Having thus described my invention, I claim:

1. In a spark plug, a removable unit including a sleeve provided with three ball electrodes extending from one end thereof and spaced approximately 120° apart and a member positioned within said sleeve and provided with three ball electrodes positioned approximately 120° apart and each 105 designed to be positioned between adjacent electrodes from the sleeve thereby to form a demountable ring of six spark gaps and stems connecting each ball electrode with its correlated sleeve or member thereby to project the electrodes from their supports and with the centers of the balls disposed in a 110 circle and equally spaced.

2. A spark plug having a slightly concaved recess at one end, and a ring of spaced 115 apart electrodes protected within said recess, said plug comprising a containing shell, a sleeve fitted in said shell and an insulating core fitted within said sleeve, said shell, sleeve and core having recessed ends coaxially designed to form the said electrode containing recess, said sleeve provided with one of the electrodes forming said ring and a conductor passing through said core and provided with another of the electrodes 125 forming said ring.

3. A demountable unit constituting part of a spark plug and designed to fit in a containing shell, said unit comprising a member provided with a plurality of ball 130

points, a second member provided with a plurality of ball points, said ball points designed to be arranged in a circle with each of the ball points of one member disposed 5 between a pair of ball points of the other member.

4. A spark plug comprising a containing shell provided with means for mounting the same in position, a unit frictionally connected to said shell and comprising three elements, two of said elements constituting conducting members and each of said two elements provided with a ball point projection constituting a terminal point designed 15 coaxially to form a plurality of spark gaps, and the third element constituting an insulation designed, when assembled with the conducting members to extend substantially the entire length of one of the conducting 20 members, except its terminal point, thereby to insure the insulation of the members from each other, the upper end of said third element extending above the other conducting

member thereby to provide an insulated handle for removing said third element. 25

5. A spark plug comprising a containing shell provided with a frusto-conical bore constituting a seat, a frusto-conical sleeve shaped to have its entire length fit in said seat with its upper end spaced below the top 30 of the shell and provided with an electrode extending from the reduced end thereof, an insulating core having a portion designed to fit in said frusto-conical sleeve and to cover the wall forming the bore of the sleeve 35 and a rod passed through said core substantially contained therein and provided with an electrode designed to coact with the first named electrode to form a spark gap.

Signed at East Orange in the county of 40 Essex and State of New Jersey this twenty-fifth day of May, A. D., 1915.

WALLACE WILLETT.
